US0D1011345S

(12) **United States Design Patent** (10) **Patent No.:** **US D1,011,345 S**
Lu et al. (45) **Date of Patent:** ** Jan. 16, 2024

(54) **PORTABLE MONITOR**

(71) Applicant: **Shenzhen G-world Technology Incorporated Company**, Shenzhen (CN)

(72) Inventors: **Yi Lu**, Guangdong (CN); **Chuan Song**, Guangdong (CN)

(73) Assignee: **Shenzhen G-world Technology Incorporated Company**, Shenzhen (CN)

(**) Term: **15 Years**

(21) Appl. No.: **35/515,537**

(22) Filed: **Oct. 24, 2022**

(80) **Hague Agreement Data**

Int. Filing Date: **Oct. 24, 2022**

Int. Reg. No.: **DM/224550**

Int. Reg. Date: **Oct. 24, 2022**

Int. Reg. Pub. Date: **Nov. 11, 2022**

(51) **LOC (14) Cl.** **14-02**

(52) **U.S. Cl.**

USPC **D14/374**; D6/308

(58) **Field of Classification Search**

USPC D14/126, 305, 307, 315–319, 335–337, D14/339–340, 345, 371–386, 448, D14/451–452; D24/160, 186; D20/20, D20/42; D6/300, 310

CPC G06F 1/1601; G06F 1/1641; G06F 1/1654

(57) **CLAIM**

The ornamental design for a portable monitor, as shown and described.

DESCRIPTION

1. Portable monitor

1.1 : Perspective

1.2 : Perspective

1.3 : Front

1.4 : Back

1.5 : Left

1.6 : Right

1.7 : Top

1.8 : Bottom

The figures include surface shading, which represents contours and not surface ornamentation. The broken lines are included for the purpose of illustrating portions of the portable monitor and from no part of the claimed design; the

(Continued)

additional broken lines in the figures depicting a protective case illustrate environmental subject matter that forms no part of the claimed design.

1 Claim, 8 Drawing Sheets
